BY *George C. St. Louis*
ATTORNEY

UNITED STATES PATENT OFFICE

GEORGE C. ST. LOUIS, OF FRESNO, CALIFORNIA

AIRPLANE

Application filed August 8, 1930. Serial No. 473,936.

This invention relates to airplanes, and particularly represents improvements over the structure shown in my Patent No. 1,749,047 dated March 4, 1930; and also includes features shown in my Patent No. 1,685,888 dated October 2, 1928.

The principal object of the present invention is to so construct the wings of the airplane that the lifting capacity of the same is increased both over the ordinary airplane and over my own previous device. This enables the spread or area of the wings to be reduced considerably, especially as to their width; or if the conventional width is retained, to enable the airplane to carry a larger load than can at present be done.

A further object of the invention is to produce a simple and inexpensive device and yet one which will be exceedingly effective for the purpose for which it is designed.

These objects I accomplish by means of such structure and relative arrangement of parts as will fully appear by a perusal of the following specification and claim.

25 In the drawings similar characters of reference indicate corresponding parts in the several views:

Fig. 1 is a perspective view of my improved airplane as in flight.

30 Fig. 2 is a side elevation of the airplane as on the ground.

Fig. 3 is a transverse section of one of the wings.

Referring now more particularly to the 35 characters of reference on the drawings, the numeral 1 denotes the fuselage of the airplane, of any suitable form and having the usual tractor propeller 2 at the front. The wings W, preferably three in number, are all

40 the same size and are arranged in longitudinally separated relation to each other. This relation is such that the front and rear wings are spaced apart a distance substantially equal to the length of a wing; said front and

45 rear wings being on substantially the same level, while the central wing is disposed in vertical alignment with but spaced a certain distance above the space between said front and rear wings, as plainly shown in Fig. 2.

50 The various wings are pivoted at one end

onto suitable supports 3 projecting upwardly from the fuselage and are all operatively connected, so that their angularity may be altered by a suitable manually operated control means, which is indicated generally at 4, and which is fully shown and described in the above mentioned Patent No. 1,685,888.

Depending from the under surface of each wing are longitudinally extending air deflector plates 5. These plates are substantially triangular in form, extending from the front to the rear edge of the wing and sloping downwardly and rearwardly from their apex at the forward edge of the wing. These plates are arranged in cooperating pairs, the plates of each pair being connected to each other throughout the length of their lower edges, but diverging from each other from front to rear or in a longitudinal plane, as well as from their lower edges toward the 70 top or in a vertical plane. The wing surface is cut away between the adjacent plates so as to leave triangular openings in said surface as at 6, extending from front to rear of the wing; said openings being widest at the rear, 75 and the vertical space between the plates at the back being also freely open. Triangular shaped pockets, open along the top and at the rear are therefore formed.

By reason of this arrangement the same 80 benefits are obtained as were had in said Patent No. 1,749,047, namely the air passing under the wings in the troughs 8 formed between the cooperating pairs of plates will be gradually deflected laterally and compressed until by the time the air reaches the rear edges of the wings and is released, it will be compressed to such an extent that it exerts a much greater lifting effect on the wings than would otherwise be the case. At 85 the same time the compressed air currents passing rearwardly of the wing, have the effect of drawing currents of air down and along the pockets 7 which are disposed between the compressed air currents, an action 90 which is enhanced by the peculiar shape of the pockets, which increase in width and depth to their rear open ends, at which ends they are influenced by said compressed air 95 currents.

This causes a tendency to vacuum to be created above the wings so that the downward pressure of the air thereon is relieved. This feature also obviously increases the lifting power of the wings, which, as above stated, is 5 already increased over what is at present obtained by the compressed air under the same.

It will therefore be seen that by thus increasing the pressure of the air under the 10 wings and lowering it above the wings, said wings will have relatively great lifting power for their size, and such size may therefore be comparatively small as compared to the wing area of an ordinary airplane, for the 15 same given lifting capacity. The particular arrangement of the wings relative to each other while providing a substantially continuous lifting or supporting surface throughout the length of the airplane, enables the air compressing and vacuum forming feature of each wing to function without interference from an adjacent wing.

From the foregoing description it will be readily seen that I have produced such a 25 device as substantially fulfills the objects of the invention as set forth herein.

While this specification sets forth in detail the present and preferred construction of the device, still in practice such deviations 30 from such detail may be resorted to as do not form a departure from the spirit of the invention, as defined by the appended claim.

Having thus described my invention what I claim as new and useful and desire to secure by Letters Patent is:

An airplane wing comprising a plurality of plane surfaced members meeting together to form a common straight leading edge and each tapering rearwardly from such edge to 40 form individual straight trailing edges with substantially V-shaped open spaces between the adjacent edges of the members, deflector plates depending downwardly and outwardly from the edges of the members and those 45 plates between the members meeting at their lower edges below such V-shaped openings.

In testimony whereof I affix my signature.
GEORGE C. ST. LOUIS.
